UNITED STATES PATENT OFFICE.

WILLIAM HEAP AND WILLIAM ALFRED BARNES, OF BOLTON-LE-MOORS, ENGLAND.

COMMUTATOR-BRUSH HOLDER.

SPECIFICATION forming part of Letters Patent No. 781,650, dated February 7, 1905.

Application filed August 15, 1904. Serial No. 220,727.

To all whom it may concern:

Be it known that we, WILLIAM HEAP and WILLIAM ALFRED BARNES, subjects of the King of Great Britain and Ireland, and residents of Horwich, Bolton-le-Moors, England, have invented certain new and useful Improvements in Commutator-Brush Holders, of which the following is a specification.

This invention has for its object to provide a brush-holder for dynamos and the like which shall possess a minimum of parts and be extremely simple of construction, yet provide for all the necessary adjustments and conditions for the effective use of the holder.

Upon the accompanying drawings, Figure 1 illustrates a right-hand side elevation, and Fig. 2 a plan, of the improved holder. Fig. 3 illustrates a left-hand longitudinal section, and Fig. 4 an end view.

According to the invention the holder comprises two arms or cheeks *a*, of thin metal, joined by a floor part *b*. At their wider ends the arms are bored to loosely fit the brush-spindle *d*. Between the arms and surrounding the spindle *d*, also fixed thereto by a taper pin *e*, is a sleeve *f*, and in one with such sleeve is a segmental ratchet-wheel *g*. Also between the arms *a* and loosely fitting the reduced ends of the sleeve *f* are two lever-arms *h*. Pivottally mounted between the arms *h* is a pawl *i*. Pivottally mounted between the cheeks *a* is a lever *j*, and between such lever and a lever-like extension of the pawl *i* is a spiral spring *k*. The lever *j* has a short 5 arm *j*^x, and such arm pokes through a slot *l* in a plate *m*, slidably supported upon the floor part *b*. This plate at its forward end is of hook formation, and upon the under face of the floor part *b* is a ridge or projection *b*^x.

Between and by this latter and the hooked end of the plate *m* the carbon block or brush *o* is held, the rear part of the block and the space between the gripping parts being of dovetail shape, as shown, to insure the secure 5 attachment of the block. With the block *o* in contact with the commutator *n* and the pawl *i* engaging the ratchet-segment *g* the

spring *k* is in compression. Hence by tending to separate the lever *j* and pawl *i* it serves both to put a pressure on the brush and, through 50 the small arm of the lever *j*, to put a tension on the plate *m*, and thus maintain a grip on the block. By altering the position of the pawl *i* relatively to the ratchet-segment *g* the pressure of the brush on the commutator is 55 correspondingly increased or decreased, while by allowing the pawl to engage, say, the last few teeth the holder is free to rise to the position shown in Fig. 3, the friction of the pawl with the teeth of the ratchet-segment being 60 sufficient to sustain it in the elevated position. Upon the arms *h* are projections *h*^x, which when the tension is taken off the brush come against the holder and raise it, (see Fig. 3,) the tension on the brush or the range of movements being comparatively slight. To keep the plate *m* to its work, it passes below a cross-pin *p* and below the boss of the lever *j*.

In view of the radial adjustments the lever *j* and the extension of the pawl are formed 70 with small cup-like perforations *q*, into which the ends of the spring *k* fit and to one or both of which the spring is permanently secured, so as to prevent its accidental dislodgment.

It will now be seen that we get a holder 75 which affords a variable pressure to the brush, which enables all the adjustments to be effected by hand, enables the carbon to be readily renewed, and is composed of very few parts for the various adjustments.

What we claim is—

A brush-holder comprising two metal and tapering arms with holes to fit the holder-spindle, and a floor part joining such arms, a plate 85 slidably fitted between the said arms and against the said floor part and the end of the plate and the floor part so formed as to produce a vise for holding the "brush," a spindle on which the said arms are mounted, a sleeve part also fitting the spindle and lying between 90 the two arms of the holder, a segmental ratchet-wheel secured to the sleeve part, a pair of arms loosely mounted on the ends of the said sleeve part, a pawl carried by the last-

named arms, and said pawl formed with a lever-like extension, a double-armed lever pivotally supported between the said holder-arms, and with one arm engaging the aforesaid sliding plate, and the other arm lying directly opposite the lever-like extension on the pawl, and a spiral spring lying between the said extension and lever-arm, as set forth.

In witness whereof we have hereunto set our hands in the presence of two witnesses.

WILLIAM HEAP.

WILLIAM ALFRED BARNES.
